UNITED STATES PATENT OFFICE.

JOHN D. WARREN, OF BURLINGTON, IOWA.

DESIGN FOR A WALL-FIXTURE FOR STORES.

SPECIFICATION forming part of Design No. 22,962, dated December 12, 1893.

Application filed August 11, 1893. Serial No. 482,946. Term of patent 7 years.

To all whom it may concern:

Be it known that I, JOHN D. WARREN, a citizen of the United States, residing at Burlington, in the county of Des Moines and State of Iowa, have invented and produced a new and original Design for Wall-Fixtures for Stores, of which the following is a specification, reference being had to the accompanying drawing, showing a part thereof

10 The accompanying drawing is a perspective view of my new design for a wall fixture.

My new design for a wall fixture for stores consists essentially of a base A, with drawers B, B, in a number of sections arranged side by side. Over one section of the base is a case provided with doors C exposing the in-

terior; over another base section a system of paneled front drawers D, exposing the interior. Between the case sections are panels E, having mirrors F, and on front of these are arranged shelves G. The sections of the case are also surmounted by skeleton shelving, as shown. Panels I are also arranged at the ends of the cabinet, provided with mirrors J, and supporting shelves K.

25

I claim as my invention—

The design for a wall fixture for stores, substantially as herein shown and described.

JOHN D. WARREN.

In presence of—

R. M. GREEN,
H. W. GRETZINGER.
